Inventor:
Andrew Knierim,
by *Andrew S. Knierim*
His Attorney.

UNITED STATES PATENT OFFICE.

ANDREW KNIERIM, OF SCHENECTADY, NEW YORK, ASSIGNOR TO GENERAL ELECTRIC COMPANY, A CORPORATION OF NEW YORK.

REFINISHING TOOL FOR SWITCH CONTACT RODS.

Application filed April 8, 1924. Serial No. 705,110.

My invention relates in general to electric switches and particularly to a tool for sharpening or refinishing the ends of the contact rods of fluid break switches. Under severe operating conditions these rods sometimes become burned at their ends with the result that the roughened surface interferes with the entry of the rod into the corresponding socket contact. By the use of the tool disclosed herein the ends of these rods may be readily refinished with a smooth surface of the proper curvature.

My invention will be better understood by reference to the accompanying specification and drawing and its scope will be pointed out in the appended claims.

In the drawing, Fig. 1 is a perspective view of the complete tool comprising my invention; Fig. 2 is a disassembled view of the parts comprising the tool; and Fig. 3 is a fragmentary sectional view of the tool showing also the end portion of a burned contact rod.

Referring now to the drawing, the tool consists of three parts, the body 1, the cap 2, and the cutting blade 3. The body is in the form of a hollow cylinder, the opening of which is of such a size as to freely receive the switch contact rod 4. The upper end of the body has an exterior right-handed screw thread and the cap is interiorly threaded whereby they are secured together. Two opposite longitudinal slots 5 are provided in the upper end of the body, which slots receive the cutting blade and the ends of these slots constitute limiting surfaces 6 against which the lower end of the cutting blade is clamped. The blade 3 which may be of steel has two oppositely beveled cutting faces 7 shaped to produce the desired curvature on the end of the contact rod 4. The opposite end of the blade is shown somewhat pointed to conform to the conical inner surface 8 of the cap. For rotating the tool the cap is pro-

vided with a shank 9 having a squared portion 10. The body of the tool is shown provided at its upper end with observation openings 11. It will be noted that when the cap is screwed down upon the body, the blade is securely clamped in place and since the screw threads on the body and cap are right-handed there is no tendency for the cap to loosen upon a right-handed rotation of the tool.

While I have described only one embodiment of my invention, I do not wish to be limited to the particular form shown and described as it will be apparent that many modifications therein may be made without departing from the scope of my invention as set forth in the appended claims.

What I claim as new and desire to secure by Letters Patent of the United States, is:—

1. A device of the character described comprising a tubular body member having longitudinal slots formed therein at one end, a transverse removable blade engaging in said slots and having a cutting notch at one end, and a cap screw threaded on the end of the tubular body member for engaging opposite edges of the blade to center the same in the body and for engaging the end of the blade to firmly clamp it to the body.

2. A tool of the character described comprising a tubular body member having its walls at one end slotted longitudinally, a cutting blade having beveled cutting edges formed at one end thereof and having its side edges engaging in the slots in said body member, and a cap screw-threaded on the slotted end of said body member whereby said blade is firmly clamped to said body member, said cap having a shank terminating in a polygonal portion by which the tool may be rotated.

In witness whereof, I have hereunto set my hand this 7th day of April, 1924.

ANDREW KNIERIM.
